UNITED STATES PATENT OFFICE.

GEORGE W. HAMILTON, OF ALTOONA, PENNSYLVANIA.

DESIGN FOR A CLOCK CASE AND DIAL.

No. 39,922.

Specification for Design.

Patented April 20, 1909.

Application filed March 30, 1908. Serial No. 424,292. Term of patent 14 years.

To all whom it may concern:

Be it known that I, GEORGE W. HAMILTON, a citizen of the United States, residing at Altoona, county of Blair, and State of Pennsylvania, have invented a new, original, and ornamental Design for a Clock Case and Dial, of which the following is a specification, reference being had to the accompanying drawings, forming part thereof.

In the drawings: Figure 1 is a front elevation of a clock case and dial showing my new design. Fig. 2 is a side elevation thereof.

The distinguishing features of the design forming the subject matter of this application are an upright oblong case having a py-

ramidal cap portion, a squared paneled base and transparent rectangular panels in the front and sides thereof, the front transparent panel bearing thereon a plurality of concentric circular figures within the field of which are arranged a circular series of numerals in clock-dial order.

I claim:

The ornamental design for a clock case and dial, as shown and described.

GEO. W. HAMILTON.
